LAMP WITH INTEGRAL COOLING RADIATION

George M. Dinnick, Bloomfield, N. J., assignor to
Westinghouse Electric & Manufacturing Company, East Pittsburgh, Pa., a corporation of Pennsylvania

Application December 30, 1938, Serial No. 248,398

7 Claims. (Cl. 176—16)

The invention relates to incandescent electric lamps and particularly to such of the gas-filled type which is apt to have bulb blackening.

5 The principal object of my invention is to prevent the condensation of filament material on the portion of the container utilized for the production of light.

Another object of my invention is to remove 10 excess heat from incandescent electric lamps while in operation and thus provide a greater protection to the lamp parts and also to permit the utilization of a greater amount of energy without danger to these same lamp parts.

15 Specifically, it is an object of my invention to provide a metal portion of the lamp wall for the purpose of having a cooled portion in the natural or directed path of the inner gas currents within the tube so that any particle from the filament will condense upon this metal portion and not upon the portion of the container utilized for the projection of light therethrough. The transfer of heat through this metal portion also aids in protecting the other tube parts from overheating.

20 25 Other objects and advantages of the invention will be apparent from the following description and drawing, in which:

Fig. 1 is a cross-section through a tube embodying the invention.

0 Fig. 2 is a top elevational view of Fig. 1.

Figs. 3 and 4 are partial views in cross-section illustrating modifications of the invention disclosed in Fig. 1.

In ordinary practice the metal evaporated 5 from the incandescent filament in a lamp is deposited on the bulb wall causing an appreciable loss in lumen output due to absorption of light by the deposited material. This light absorption also increases the bulb temperature in some 10 cases to such an extent that the glass softens or becomes distorted and blows out due to the difference between the atmospheric pressure and the pressure inside the lamp.

To diminish the amount of material deposited 15 on the bulb and consequently to improve the lumen maintenance and to reduce the bulb temperature, I propose to insert a metal casing portion for a portion of the insulating material in the type of lamp which is particularly subject to bulb blackening.

In Fig. 1, I have disclosed the lamp 10 comprising an envelope or bulb 11 mainly of translucent insulating material such as glass and mounted on a base indicated at 12 and enclosing a mount 13. The mount of the present embodiment comprises the flared tube 14 sealed to the bulb and provided with an exhaust tube 15 and lead-in conductors 17 and 18 extending through the press from the base 12 and connected to the filament 16. This filament 16 has supports 19, 5 which are in turn, supported from an arbor 20 on the flared tube 14.

It will be noted that the tube 10 has an elongated axial aligned casing supported on the base 12 at one end. The filament in the intermediate portion is for the projection of light through the translucent glass tube walls adjacent the filament. The upper end of the tube has a metal casing portion 21 preferably of copper and sealed with the well-known feather edge seal 22 to the glass portion of the tube container. This metal, while preferably of copper because of its high quality of heat transference, may be of other materials that seal to glass such as the iron-nickel-cobalt alloy known under the trade name 20 of "Kovar" and described in the patent to Howard Scott, No. 2,062,335, issued December 1, 1936. This metal casing portion 21 has preferably exterior fins 23 extending upwardly and also laterally as disclosed in Fig. 1 and in the top view 25 disclosed in Fig. 2. The metal casing portion also preferably has an interior fin 24 as disclosed in Fig. 1, and in dotted lines in Fig. 2, extending across the center portion of the tube. The interior tip end 25 of this interior fin is preferably pointed or tapered and is located in axial alignment with the center portion of the filament. As disclosed in Fig. 1, this interior fin divides the interior portion of the metal into two compartments. The tube 10 is generally filled 30 with an inert gas such as argon or nitrogen and under the heat of operation, flow or convection currents are created inside of the tube. The fins 23 provide a natural radiation of the heat from the interior of the tube and of course, this radiation may be aided by artificial means such as a fan blowing air on the fins, or by water cooling. It is possible to substitute coils containing a liquid medium, such as water, for the fin 23. The cooled portion of the interior atmosphere 35 will naturally drop downward along the inner surface of the tube wall as disclosed by the arrows 26, while the hot filament will send a hot current of gas upward as indicated by the arrows 27. The interior fin 24 will aid in dividing this 40 hot current of gas and directing it on either side thereof over the full inner surface of the metal casing 21 to effectively remove the heat therefrom. Any hot particle or vaporized portion of the filament carried along in this hot blast of 45

50 55 55 a mount 13. The mount of the present embodiment comprises the flared tube 14 sealed to the bulb and provided with an exhaust tube 15 and lead-in conductors 17 and 18 extending through the press from the base 12 and connected to the filament 16. This filament 16 has supports 19, 5 which are in turn, supported from an arbor 20 on the flared tube 14.

gas, will be deposited or condensed on the inner surface of this metal casing 21 and will not be deposited on the lateral glass portion sides of the tube 11 to darken this translucent portion. This translucent portion is, of course, translucent enough, generally, to be transparent. While I have disclosed one interior rib extending across the interior of the metal casing, other interior ribs might be used to further sub-divide the space at the top of the tube to direct the hot gas currents. From Fig. 2, it is apparent that the number of exterior fins 23 can be selected as desired.

In Figs. 3 and 4, I have made further modifications in the metal casing portion 21 for more effectively directing the hot gas currents over the cooled surface. The outer surface of the metal casing portion 21 formed into preferably a reentrant surface 30 and have thus changed the interior fin 24 into a gradually tapered or conical projection 31. I have made the reentrant portion of the metal casing in this shape to maintain the thin walls for ready heat transference although it might be possible to use a thick wall at this place forming the cone projection. This conical projection 31 provides the gentle curve 32 for directing the gas currents over the surface of the metal casing portion and effectively cooling them. As a further modification, a metal guard 33 may be secured to the inner surface of the metal casing portion 21 to protect the feather seal 22. This guard, as shown, is held in place by friction although other fastening means could be utilized. This guard will prevent heat directly striking the seal and will conduct this heat to the main body of the metal casing.

In Figs. 3 and 4, I have also illustrated the type of incandescent electric lamp used for projection purposes and consequently generally using an extremely bright filament with its consequent release of considerable heat. I have also illustrated positive means for directing the hot gas currents from this filament towards the conical projection 31. In Figs. 3 and 4, the lamp 50 comprises an envelope or bulb 51 with a base and mount similar to that of Fig. 1. The mount comprises a flared tube, similar to that illustrated and designated as 14 in Fig. 1, being sealed to the bulb and provided with an exhaust tube and an arbor or button 55 extending from the press. Leading-in conductors extend through the press from the base and connect with relatively rigid inner supporting leads 59 and 60 which may be formed of nickel or other suitable material with their normally lower ends embedded in the press. In this embodiment, the normally upper or free ends of the supporting leads 59 and 60 are connected by wires 61 and 62, the outer ends of which are spot welded thereto as indicated at 63 and 64 and the inner ends of which are embedded in an insulating member or bridge 65 which may be a piece of glass cane. Depending from the insulator 65 are a plurality of supporting members 66, 67, 68, 69, and 70, the number depending on how many coiled sections the filament 71 contains. In the present embodiment, the coiled filament 71 comprises eight coiled sections which are connected by intersection loops and staggered, so that four are disposed in one normally vertical plane and four in a normally vertical plane parallel thereto and so spaced that, in plan, they lie at the vertices or isosceles triangles.

The upper uncoiled portions of the connected 75 sections of filament 71 are draped over the hooked

or doubled-over lower ends of members 66 to 70 inclusive, as illustrated, and the extreme coiled end sections 72 and 73 forced over connecting members 74 and 75, the outer ends of which are desirably spot welded to the supporting leads 59 and 60 respectively. Outer coils 76 and 77 may be screwed over the coiled end portions 72 and 73 for short-circuiting the turns thereof to improve the uniformity of rating.

In order to hold the filament 71 in position between the leads 59 and 60 and at the same time avoid strains due to expansion and contraction of the metal parts of the lamp, a light bridge assembly 78 is provided, which preferably comprises an insulating portion 79 preferably 15 formed of a piece of glass cane, and end wires 80 and 81, the inner ends of which are embedded in an insulator 79 and the outer ends of which normally extend diagonally outward and upward and are formed with eyes or loops 20 82 and 83 to receive the supporting leads 59 and 60 respectively. The eyes or loops 82 and 83 are desirably adjusted so as to slide on the leads 59 and 60 with the avoidance of binding, even when the bridge device 78 is slightly tilted 25 with respect to said leads.

The bridge device 78 is normally suspended from the filament 71 by having members 84, 85, 86, and 87, the lower ends of which are embedded in the insulator 79 and the upper ends 30 of which are bent to hook over the loops formed between the lower portions of the coiled sections of filament 71.

In order to prevent undesired tilting of the bridge device 78, when the lamp is inclined from 35 its normal vertical base-down position, the insulator 79 is desirably provided with a bottom guide 88 slidably cooperating with the wire 89 extending upward from the arbor 55.

Inasmuch as the lamp illustrated is of the 40 type in which the filament is operated at a very high temperature to give a great amount of light with a relatively short life, the filament is desirably surrounded by an inert gas to reduce vaporization from the filament. Nevertheless, 45 vaporization takes place and I have provided the metal portion 21 hitherto described, for the purpose of condensing this vaporized material or sputtered particles thereof and in addition, I have provided means for directing any such material onto this metal portion of the tube wall. In particular, I employ plate means comprising a pair of desirably imperforate plates 90 and 91 formed of metal such as nickel or molybdenum, which plates are desirably mounted so as to normally extend above and lie on either side of the filament as shown most clearly in Figs. 3 and 4. For that purpose, the plates 90 and 91 are secured to the ends of a wire 92, as by spot welding, which wire is looped over the insulating bridge member 65 and supported therefrom as by being spot welded to a spud 93 extending upwardly from the approximate mid-portion thereof. In order to improve the connection between the wire 92 and the spud 93, the curved 60 upper portion of the said wire preferably has first applied thereto a metallic flux which may consist of a coil 94 of relatively fine wire.

As illustrated, the plates 90 and 91 are desirably disposed so that their lower edges are 70 slightly above the upper ends of the coil 71, said plates being desirably inclined with respect to one another so that the included angle is from about 20 to 30 degrees.

As illustrated, the lower edges of the plates 75

may be separated about sixteen millimeters, and the top edges about eight millimeters, although the size of the plates, and the spacing thereof, desirably varies in accordance with the size of

5 the light source in the enclosing bulb. The wire 92 is desirably extended between its curved portion and where it is connected to the plates 90 and 91, so that the plates are properly positioned with respect to the filament.

10 In Fig. 4, the side view of the tube is shown to illustrate that each plate 90 and 91 preferably has its side edges flanged inwardly, as indicated at 95 and 96 so as to close up some of the space left between said edges and thereby improve 15 the collecting characteristics of the plates.

From the foregoing disclosure, it will be seen that means are provided in the incandescent lamp structure of Figs. 3 and 4 by these plates, for directing the gas currents towards the projecting cone 31 as indicated by the arrows in Fig. 4. The interior surface of the metal casing portion is shaped as will be apparent from the drawing, for effectively cooling this hot gas current and removing therefrom any sputtered or 25 vaporized filament particles.

It is apparent that still further modifications might be made in the preferred embodiments illustrated in the drawing without departing from the spirit of the following claims.

30 I claim:

1. A lamp comprising a filament, a casing with an inert gaseous atmosphere enclosing said filament and having a translucent portion adjacent said filament and a metal portion sealed to said translucent portion, said metal portion having interior fins.

2. A lamp comprising a filament, a casing with an inert gaseous atmosphere enclosing said fila-

ment and having a translucent portion adjacent said filament and a metal portion sealed to said translucent portion, said metal portion having interior and exterior fins.

3. A lamp comprising a base on one end and a casing at the middle and other end, said middle having a translucent part of the casing and said other end having a metal part of the casing, fins on said metal part, and an inert gaseous atmosphere in said casing.

4. A lamp comprising an extended axially aligned casing, a gaseous atmosphere therein, a filament along the axis of said casing, means directing the gaseous atmosphere currents, heated by said filament, along the axis of said tube, and a metal portion of the casing terminating the axis of the casing towards which said gaseous atmosphere currents are directed.

5. A lamp comprising a filament, a casing with an inert gaseous atmosphere enclosing said filament and having a translucent portion adjacent said filament and a metal portion sealed to said translucent portion, said metal portion having an interior reentrant surface.

6. A lamp having a base, a casing with an inert 25 gaseous atmosphere supported by said base, a filament within the casing, said casing being translucent about said filament and the opposite end of said casing from said base being of metal.

7. A lamp having a base, a casing with an 30 inert gaseous atmosphere supported by said base, a filament within the casing, said casing being translucent about said filament and the opposite end of said casing from said base being of metal, and having a reentrant surface having a projec- 35 tion towards said filament.

GEORGE M. DINNICK.
